UNITED STATES PATENT OFFICE.

JOHN H. PILLINGS, OF DAYTON, OHIO, ASSIGNOR OF ONE-HALF TO BENJAMIN H. NOYES, OF DAYTON, OHIO.

AUTOMATIC OPERATING MECHANISM FOR TYPE-WRITERS.

1,208,640.

Specification of Letters Patent.

Patented Dec. 12, 1916.

Application filed September 29, 1913. Serial No. 792,368.

To all whom it may concern:

Be it known that I, JOHN H. PILLINGS, a citizen of the United States, residing at Dayton, in the county of Montgomery and State of Ohio, have invented certain new and useful Improvements in Automatic Operating Mechanism for Type-Writers, of which the following is a specification, reference being had therein to the accompanying drawing.

This invention relates to automatic operating mechanism for typewriters.

Mechanisms have been produced heretofore for automatically operating typewriters to produce form letters, circulars or other matter of which a plurality of copies is desired. These devices, however, for the most part, if not exclusively, rely upon either electricity or air in their operation and a perforated web of paper for controlling the operation. More or less successful operation has been attained by these mechanisms but they are complicated and require such delicate adjustments that they give trouble in actual service, it requiring the services of a skilled mechanic to maintain them in proper working condition. Moreover, it is necessary to prepare a perforated controlling sheet or web for each letter which is to be written and this in itself is an expensive proceeding, and moreover when the sheet has been once perforated it is very difficult to make corrections or alterations therein and the sheet itself is easily damaged and short lived.

The object of the present invention is to provide an automatic operating mechanism which will be mechanical throughout its construction and which will be of a simple character and durable construction.

A further object of the invention is to provide such a mechanism which can be applied to a typewriter without material modification of the construction thereof and without interfering with the manual operation of the typewriter in the ordinary manner.

It is also an object of the invention to provide a controlling device having movable parts which may be adjusted to set up the letter or form, and which will be of such a character that an unlimited number of copies can be taken therefrom.

Further, it is an object of the invention

to make this controlling device removable so that a given letter may, if desired, be removed and preserved until it is desired to use the same at a future time.

In the accompanying drawings, Figure 1 is a front elevation of a device embodying my invention; Fig. 2, is a top, plan view of the mechanism with the typewriter removed; Fig. 3 is a vertical sectional view, taken longitudinally of the mechanism; Fig. 4 is a detail view of the trip mechanism forming a part of the carriage return devices; Fig. 5 is a sectional view showing in elevation the selective actuating mechanism and the mechanical controlling devices therefor; Fig. 6 is a detail view of the tabulator lock; Fig. 7 is a view similar to Fig. 5 showing the actuating mechanism set for operating a selected type bar. Fig. 8 is a transverse, sectional view showing in detail the actuating bar and the devices for operating the same; Fig. 9 is a fractional view of the controlling drum showing the means for advancing the same step by step during the setting up operation; Fig. 10 is a detail view of one of the adjustable tripping devices forming a part of the controlling device; Fig. 11 is a transverse, sectional view showing the device for connecting and disconnecting the controlling device with the selective actuating mechanism; Fig. 12 is a plan view of the connecting devices between the controlling device and the actuating mechanism; Fig. 13 is a similar view showing the connecting devices in their inoperative positions; Fig. 14 is a plan view of a portion of the drum and the guides and showing the devices for setting and stripping the trip devices on the drum; Fig. 15 is a sectional, detail view of the carriage-controlling mechanism; Fig. 16 is a transverse, sectional view showing the construction of the drum; Fig. 17 is a detail view of one of the operating devices for the actuating carriage; Fig. 18 is a detail view showing a modified form of mechanism for actuating the controlling lever.

In carrying out the invention I provide two principal mechanisms. First, a selective actuating mechanism which will select and operate the desired one of the key bars and their connected elements; and second, a mechanical controlling device for this selective actuating mechanism which will de-

termine which key bar is to be operated and which can be set up to cause the successive operation of a series of key bars and thus cause the typewriter to write a given word, sentence or letter. These two mechanisms may be of any suitable construction and that embodiment of the invention shown in the accompanying drawings has been chosen for the purpose of illustration only.

10. As here shown the operating mechanism as a whole is mounted upon and preferably within a supporting frame 1 which is preferably inclosed by a cabinet 2. A typewriter of any construction, such as the ordinary commercial machine, is mounted adjacent to the supporting frame and preferably upon the same, as shown in the drawings at 3. Inasmuch as the typewriter is of ordinary construction it is unnecessary to 20 describe the details thereof. Suffice it to say that it comprises the type bars 4 which are connected with and operated by key bars 5 provided with finger keys 6. It also embodies various other key-operated mechanisms, such as the carriage shifting mechanism, spacing bar, etc. It will be understood that the term "key bar" as employed in this specification and the appended claims includes not only the key bar for actuating 30 the type bars but also includes any device which may be actuated manually to cause the operation of some part of the typewriter. By means of the present invention all of the key-operated functions are automatically performed and this performance is preferably accomplished by causing the key bars to be actuated in substantially the same manner that they are actuated when the machine is manually operated. The 40 mechanism is connected with the typewriter with practically no change therein, although I have added to the typewriter mechanism certain parts to coöperate with the automatic mechanism.

45. The present invention does not contemplate the feeding of the paper to the typewriter automatically, although, of course, this can be accomplished by any suitable sheet or web feeding mechanism. Neither does the device contemplate automatically writing in the addresses on the letters, although, if desired, this can also be done. I prefer, however, that the operator should manually write in each address and then 55 start the automatic mechanism which will write the letter in its proper position relatively to the address. In this manner the whole letter, superscription and all, is written on the same machine and there is, 60 of course, no difference whatever in the appearance of the different parts thereof. A single operator can take care of a battery of machines, the number depending upon the length of the letter, and in this way 65 an ordinary card address list may be em-

ployed and the changes made therein with the ease and facility that they are made in such lists under ordinary circumstances.

As stated above the selective operating mechanism may be of any suitable construction but I prefer that it should be mechanical throughout and, as here shown, it comprises a continuously moving actuating member which is in the form of a vertical reciprocating bar 7 mounted in guideways 70 8 at the opposite sides of the frame 1 and connected with a suitable operating mechanism for imparting reciprocating movement thereto continuously while the machine is in operation. In the present machine the slide 75 bar is connected by means of connecting rods 9 with eccentrics 10 on a shaft 11 journaled in bearing plates 12 carried by the opposite side members of the frame, and driven from a motor 13 by means of a belt 80 14 extending about a belt wheel 15 secured to the end of the shaft 11. In the absence of an operative connection with the controlling device the vertical, reciprocating movement of the actuating member or bar 90 7 has no effect upon the mechanism of the typewriter. This bar is provided with a plurality of movable fingers, 16, the number of the fingers corresponding to the number of parts to be operated, or, key bars, in the 95 typewriter. When it is desired to operate a particular key bar its corresponding finger 16 is moved into operative relation therewith and the reciprocation of the actuating member 7 causes the operation of 100 the key bar and its connected parts. In the present form of the machine the actuating fingers 16 are pivotally mounted upon the actuating bar at their upper ends on a substantially horizontal axis extending parallel 105 with the shaft 11 and are held normally in a substantially vertical position, which is their inoperative position, by means of springs 17 mounted upon the actuating bar and engaging the respective fingers. To 110 connect the actuating fingers 16 with the respective key bars, each finger is provided with a connecting member or lever 18 which is shown as pivotally supported at one end in the rear of the actuating member and 115 as having its opposite end arranged in front of the actuating member and connected by means of a suitable connecting device or link 19 with the corresponding key bar. The connecting links 19 may be of any suitable character but I prefer that the same should be formed with open slots at their upper ends through which the respective key bars extend, as this permits the key bars to move downwardly independently of the 120 links and their connecting mechanisms and thus enables the typewriter to be manually operated while connected with the automatic mechanism. The lower end of each link is also slotted to receive the end of its 125

connecting lever and may be provided with a set screw 20 to adjust the same relatively to the lever. The connecting levers 18 are arranged in the same vertical planes with the respective actuating fingers 16 and each lever is provided with a depressed portion forming a recess 21, into which the lower end of its actuating finger extends, upon the downward movement of the actuating bar, 10 without engaging the lever. When it is desired to operate a particular lever the corresponding actuating finger 16 is moved about its axis to bring the lower end thereof into alignment with that portion of the connecting lever lying immediately in front of the recess, whereby the downward movement of the actuating bar will cause the finger to engage the lever and depress the same.

15 It is desirable that some means should be provided for retaining the finger in operative engagement with the lever during the downward stroke of the actuating bar and after the finger has been released from the device which moved it into its operative position. To this end I have formed a projection or lip 22 at the forward edge of the recess 21 and have notched the lower end of the finger 16, as shown at 23, so that 20 when the finger is in operative relation to the lever the lip will enter the notch and this interlocking engagement of the parts will retain them in operative relation until the actuating bar is again moved upward 25 to disengage the two parts.

A suitable controlling device is provided to cause the actuating fingers to be moved into operative relation with their respective levers in proper sequence. Various forms 40 of controlling devices may be used for this purpose but that here shown embodies a principle especially adapted for this purpose and is of such a character that it can be utilized to control a selective actuating mechanism, such as is here shown or other suitable actuating mechanism, and either directly or through interposed connecting devices. For the purpose of the present machine I have illustrated the controlling 45 device as acting through certain connecting devices which will be hereinafter described and I have shown the controlling device as comprising a movable member having adjustable parts and have illustrated this 50 movable member as consisting of a cylinder 24 rotatably mounted upon a shaft 25 and adapted to be rotated either continuously or intermittently. To impart continuous rotary movement to the drum I have 55 provided the same about its periphery near one edge thereof with an annular rack 26 which meshes with a pinion 27 on a short shaft 28 journaled in one of the bearing brackets 12 and having a worm wheel 29 meshing with a worm 30 on a shaft 31 hav-

ing secured thereto a bevel gear 32 which meshes with a corresponding gear 33 on the shaft 11 which, as above explained, is rotated from the motor. In Fig. 18 I have shown a device by means of which intermittent movement may be imparted to the drum or movable member and this mechanism comprises a pawl 34 having its nose arranged to engage the teeth of the rack 26 and having its opposite end connected to one 75 arm of a bell crank lever 35, the other arm of which is adapted to be engaged by a cam 36 secured to a rotatable shaft, such as the shaft 11. The bell crank lever and the pawl may be either positively returned 80 by the cam or returned by a spring, as shown at 37. It will be understood, however, that the character of the movable member may be widely varied from that here shown and that it may be driven in any 85 suitable manner, either continuously or intermittently.

The movable member of the controlling device, whether in the form of a drum or otherwise, has a plurality of controlling members or tripping devices arranged in positions to operate the key bars in the proper sequence to produce the desired subject matter or letter on the typewriter. Preferably, but not necessarily, these controlling members are adapted to be adjusted to different points across the width of the drum to enable their positions to be changed so that the controlling device may be set to cause the operation of the key bars in different sequence to produce copies of different letters. When the controlling members or tripping devices are adjustable the construction and arrangement are such that they are normally held against displacement, thus enabling the type-operating devices to be actuated in the same sequence upon each successive movement of the controlling device. Of course, when the controlling members are not adjustable the same 100 result is obtained. These adjustable tripping devices may be of any suitable character and mounted in any suitable manner, but in the present instance, the movable member is provided with a series of transverse slots, 105 as shown at 38, spaced short distances apart and extending for substantially the full width of the drum. Mounted in these slots and adapted to be moved therein transversely of the drum are a series of plates 39 having projections 40 adapted to extend beyond the surface of the movable member or drum. There is one of these trip devices, or for the sake of brevity, trips, in each slot, and it can be moved along the slot to 110 any desired position. To retain the trip devices in their adjusted positions and prevent the radial displacement thereof during the operation of the device the drum is surrounded by a series of ribs 38a spaced 115

apart to form slots into which the projections or trips extend which are thereby held against movement relatively to the drum. In the present form of the actuating mechanism these trips are not adapted to engage directly with the actuating devices and I have, therefore, interposed suitable connecting devices which in the form here illustrated comprise a series of tripping levers 41 mounted on a single transverse axis, as indicated at 42. These levers are in the form of bell crank levers and each has a forwardly projecting arm 43 extending along the surface of the drum and having its end arranged close thereto and inclined in such a manner that when engaged by one of the trips the arm will be raised to rock the lever about its axis and permit the trip to move past the same. A spring 44 bearing against the upper arm 45 of the tripping lever tends to hold the lever normally in a position to be engaged by a trip. The tripping levers correspond in number with the actuating fingers 16 and suitable means are provided whereby the movement of one of these levers about its axis will move the corresponding actuating finger into operative relation with its connecting lever and thus cause the operation of the corresponding type bar. In the present machine this connection is formed by a sliding bar 46 mounted in suitable guideways having one end arranged adjacent to and in alinement with the corresponding actuating finger 16 and having its other end arranged adjacent to and in alinement with the upper arm of the corresponding tripping lever. Thus, the movement of the tripping lever about its axis will impart longitudinal movement to the bar 46 and, consequently, will move the actuating finger into operative position.

It is desirable that the slide bar 46 should be promptly and positively moved out of engagement with the actuating finger so as to prevent any possibility of the bar interfering with the return of the finger to its normal position. At the same time it is desirable that the bar should remain in engagement with the finger a sufficient length of time to enable the coöoperating parts of the finger and its connecting lever to be interlocked. To accomplish these two ends I have provided a locking device which will automatically lock the sliding bar in engagement with the finger and have provided the actuating bar 7 with means for releasing and returning the slide bar. As here shown each bar 46 is provided in its upper edge near that end adjacent the actuating finger with a notch 47. Extending transversely to the bars above the same and adjacent to the notch 47 is a fixed bar 48 having secured thereto a series of springs, 49, one for each slide bar 46, which springs bear upon the upper edges of the respective bars. Arranged beneath each slide bar is a second spring 50 of greater strength than the spring 49 and adapted to move the bar upward against the tension of the spring 49. When the slide bar is moved in a direction to carry the actuating finger into its operative position the spring 49 will enter the notch 47 and thus retain the bar in this position, thereby preventing the return of the finger. To release the bar and return it to its normal position the actuating bar is provided with a cam surface 51 arranged in the rear of the finger 16 and in such relation to the ends of the bars 46 that when the actuating member has been moved downward far enough to cause the finger which is in operative position to engage its connecting lever the cam will engage the end of the corresponding bar 46, move the same out of engagement with the spring 49 and force it rearward from the actuating finger, thereby permitting the return of the actuating finger to its normal position the instant it is released from its connecting lever.

It will be understood that each of the ordinary operations of the typewriter is controlled by the movable controlling member or drum and by placing the trips or projections 40 in proper position on the drum the desired operation of the typewriter will be caused when the mechanism is in operation. The letter spacing, carriage shifting, carriage return, etc., are all controlled in this manner and in order to enable the projections or trips to be readily set in their proper positions a gage is extended across the drum or movable member, as shown at 52, this gage having on its face indications corresponding to those on the key bars, and when a projection or trip has been moved into alinement with the indication on the gage it will, upon the operation of the machine, cause the operation of the key bar having that same function. To facilitate the setting of the projections or trips a slidable setting device or finger 53 is slidably mounted on a shaft 54 adjacent to the drum and in a position to engage a trip and move the same across the drum. During the setting operation the trips or projections which have not been set are moved to the right hand side of the drum into inoperative positions. To so move the projections or trips and thus clear the drum or a section thereof I have provided a second finger 55 arranged normally at the left hand side of the drum and slidably mounted on the shaft 54. The movement of this finger across the drum from left to right will carry all the projections in the path of the same to a position on the right hand side of the drum, thus clearing the drum to enable the same to be again set up. To enable the drum to be advanced step by step during the setting operation a lever 56 is mounted along the side

thereof and has a nose arranged to engage the teeth of the gear 26 and thus advance the drum one step upon each operation of the lever.

To enable access to be had to the drum for the purpose of setting up the form a transverse section of the retaining device or ribs 38^a is made removable, as shown in Fig. 14. I have also provided means whereby the connecting devices extending between the controlling member and the actuating mechanism may be rendered inoperative when this may be desired, either during the setting up of the machine or at any other time. To accomplish this I have so mounted the slide bars 46 which connect the tripping levers with the actuating fingers, that the ends of the same may be moved laterally out of alignment with the respective tripping levers, as shown in Fig. 13. To accomplish this the bars are mounted so that their rear ends may have movement relatively to the front ends thereof and in the present instance each bar is formed in two parts so that the rear portion only is moved laterally. This, however, is unnecessary to the successful operation of the device. A rod 57 extends transversely of the bars 46, is connected therewith and provided at one side of the machine with a pivoted handle 58 by means of which it may be actuated to move the bars 46 into their operative or inoperative positions. If desired, this handle may be connected with the controlling device for the motor which, in the present instance, is an ordinary electrical switch having a swinging handle to which the handle or lever 56 is connected. Thus, when the motor is cut out the connecting devices are rendered inoperative. If desired, a supplemental switch or cut-out may be interposed in the motor circuit, as indicated at 59, and controlled by a key or keys 60 on the key-board for starting and stopping the motor. Thus, the operator, after having written in an address, can by the pressure of a key start the automatic mechanism and cause the letter to be written.

A suitable mechanism is provided for automatically returning the typewriter carriage to begin a new line. Inasmuch as this operation is usually performed by grasping a part of the carriage by the hand and imparting movement thereto it will be necessary to add an actuating device for the carriage, which, as here shown, comprises a flexible member or tape 61 connected with the usual manually operated part or lever, which is shown at 62, and extending about 60 a pulley 63 and downward to a drum 64 carried by a shaft 65 mounted adjacent to the shaft 11. This drum is loosely mounted on the shaft so that the tape can readily unwind therefrom as the carriage is fed step by step across the machine. To rewind the

tape and thus return the carriage a gear 66 is loosely mounted on the shaft 65 and caused to mesh with a pinion 67 secured to the shaft 11 which, it will be remembered, is constantly rotated. The gear 66 is provided with a clutch member 68 adapted to coöperate with a clutch member 69 on the drum 64. As here shown the gear and clutch move together on the shaft 65 and the pinion 67 is wide enough to permit of the movement of the gear 66 necessary to engage and disengage the clutch members. The clutch member 68 has a grooved collar 70 with which an ordinary shifting yoke 71 is engaged. This yoke is connected with a lever 72, one arm of which is connected with a key bar 73 extending above the key-board for manual operation and is also connected with a connecting lever 18 of the actuating mechanism, whereby it may be automatically operated to move the clutch members into engagement and cause the return of the carriage when it is desired to begin a new line. The lever 72 has an upwardly extending arm 74 arranged in the path of a finger 75 mounted on the carriage and so arranged that when the latter reaches the point at which it is desired to begin the new line the lever 74 will be actuated, the clutch members disengaged and the movement of the carriage consequently checked.

The finger 75 is preferably adjustably mounted on the carriage to permit of the variation of the point at which the carriage is stopped, as shown in Fig. 4. I have also found it desirable to provide the machine with means for locking the tabulating key down until the carriage shall have been moved into engagement with the tabulating stop. In the manual operation of the machine this key is held down by the operator for a moment but the automatic operation of the key bar is so rapid that the carriage would not have time to move the necessary distance. The tabulating mechanism itself is of an ordinary character and comprises a pivoted frame 76 having the usual stops 77 and in order to lock the same in its operative position I have provided it with a slidable rod or ratchet 78 adapted to be moved into a position to engage a stop or pin 79 mounted on a fixed part of the frame. The rod is spring actuated and provided with a beveled nose so that it will automatically pass the stop on the forward movement of the rod and then move into locking engagement with the stop. To release the lock and permit the return of the tabulating device to its normal position I have provided the rod 78 with stops 80 mounted thereon adjacent to the tabulating stops but in positions to be engaged by the carriage before the tabulating stop is engaged thereby, thus releasing the tabulating device before the movement of the carriage is checked.

Ordinarily form letters and matters of a similar kind are used but once and it is not desired to preserve the form but should it be desired to preserve the same for any reason the controlling member can be readily removed and stored. In the present instance this will be accomplished by removing the shaft for the drum from its bearings and lifting the drum from the frame and then substituting another drum therefor.

The construction and operation of the machine will be fully understood from the foregoing description of the various parts thereof and it will be apparent that the operation of the device is of a mechanical construction throughout and that the operation thereof is positively accomplished; that the mechanism is of a simple, durable nature, not easily broken or disarranged, and of such a character that it can be produced at a relatively low cost; that the controlling device is of such a character as to be not only certain in its operation but will produce an unlimited number of copies; and further, that the form carried thereby can be removed and preserved if desired.

While I have shown and described one embodiment of my invention it will be understood that this has been chosen for the purposes of illustration only and that I do not desire to be limited to the details of construction, for obvious modifications will occur to a person skilled in the art. For example, it will be understood that the trip devices or trips, forming parts of the controlling device, need not necessarily actuate a movable lever but that this term is intended to include any such device which is adjusted upon the controlling member and then carried by the controlling member into a position where it will have a controlling effect upon the actuating mechanism.

Having thus fully described my invention, what I claim as new and desire to secure by Letters Patent, is:—

1. An operating mechanism comprising an actuating device adapted to be connected with any one of a plurality of devices to be operated, a movable controlling device having parts projecting therefrom, bodily adjustable thereon and positively held against displacement, and means arranged in the path of and adapted to be engaged by said parts of said controlling device, to cause operative connections to be established between said actuating device and selected devices to be operated.

2. An operating mechanism comprising an actuating device adapted to be connected with any one of a plurality of devices to be operated, a movable controlling device having parts projecting therefrom and bodily adjustable thereon, and means arranged in the path of and adapted to be engaged by said parts of said controlling device, to

cause operative connections to be established between said actuating device and selected devices to be operated, and means to retain said parts in their adjusted positions to cause said selected devices to be operated to be actuated in the same sequence by successive movements of said movable member.

3. An operating mechanism comprising an actuating device adapted to be connected with any one of a plurality of devices to be operated, a movable controlling device having parts projecting therefrom and bodily adjustable thereon, means cooperating with said parts to establish operative connections between said actuating device and the selected parts to be operated, and means to positively retain said parts in their adjusted positions whereby said selected device to be operated may be actuated in the same sequence by the successive movements of said movable member.

4. An operating mechanism comprising an actuating device adapted to be connected with any one of a plurality of devices to be operated, a movable controlling device for said actuating device having controlling members arranged in normally fixed relative positions and adjustable transversely to the line of movement of said controlling device, movable devices arranged to be actuated by said controlling members, and means operated by said movable devices to cause said actuating device to be operatively connected with selected parts to be operated.

5. An operating mechanism comprising an actuating device adapted to be connected with any one of a plurality of parts to be operated, said actuating device having a plurality of members mounted thereon and separately movable into positions to establish the connections between said device and its respective parts to be operated, a continuously moving controlling device comprising a series of controlling members, and connecting devices mounted separately from said actuating device and arranged to be engaged by said controlling member and to separately operate the movable members of said actuating device to cause the latter to be operatively connected with the selected parts to be operated.

6. The combination with a machine having operable parts, of a separate operating mechanism comprising a plurality of independently movable parts normally connected with the respective operable parts of said machine, means to impart movement to said movable parts, a continuously movable controlling device having controlling members to positively control said means, and connecting devices interposed between said controlling device and said means to cause operative movement to be imparted to a selected one of said operable parts.

7. An operating mechanism comprising

1 a main frame separate from and adapted to support the machine to be operated, a plurality of movable parts adapted to be operatively connected with the respective operable parts of said machine, and a controlling device comprising a movable member having normally fixed projections adapted to control the movements of said movable parts, said normally fixed projections being bodily adjustable transversely to the line of movement of said controlling device, and means to hold said projections in their adjusted positions.

2 8. An operating mechanism comprising 15 a main frame separate from and adapted to support the machine to be operated, a plurality of members movably mounted on said frame and adapted to be operatively connected with the respective operable parts 20 of said machine, an actuating member to impart movement to said movable members, a movable controlling device having normally fixed controlling members to positively control the operative connections between said 25 actuating member and the several movable members, said normally fixed projections being bodily adjustable transversely to the line of movement of said controlling device, and means to hold said projections in their 30 adjusted positions.

3 9. The combination with a typewriter, 35 having operable parts, an actuating mechanism comprising a plurality of parts operatively connected with the respective parts of said typewriter and a movable controlling device having a plurality of projections, each of which may be moved transversely to the line of movement of said controlling device into a position to cause a selected one 40 of the movable parts of said actuating mechanism to be operated, and means to retain said projections in their adjusted positions.

4 10. The combination, with a typewriter 45 having operable parts, an actuating mechanism comprising a plurality of parts operatively connected with the respective parts of said typewriter, and a drum having a plurality of projections adjustably mounted thereon, each projection being adapted to 50 be moved into position to cause the operation of any one of the parts of said actuating mechanism.

5 11. The combination, with a typewriter 55 having operable parts, an actuating mechanism comprising a plurality of parts operatively connected with the respective parts of said typewriter, and a controlling device comprising a movable member having a series of slots therein, and trip devices 60 adjustably mounted in said slots to cause the operation of selected parts of said actuating mechanism.

6 12. An operating mechanism for a typewriter comprising a frame separate from 65 and adapted to support the typewriter, an

7 actuating device mounted for bodily movement on said frame and having a plurality of independently movable fingers, a plurality of connecting devices supported adjacent to said actuating fingers and adapted 70 to be connected respectively with operable parts of said typewriter, and a controlling device having a part movable into different operative positions and adapted to cause a selected one of said actuating fingers to be 75 moved into operative relation with the corresponding connecting member.

8 13. An operating mechanism for a typewriter comprising a frame separate from and adapted to support said typewriter, of 80 a reciprocatory actuating bar, a plurality of independently movable fingers carried by said actuating bar, a connecting lever pivotally supported on said frame adjacent to each of said fingers, normally out of the 85 path thereof, and adapted to be connected with the operable parts of said typewriter, and means for moving a selected one of said actuating fingers into such a position that the reciprocation of said actuating bar will 90 cause said finger to engage its connecting lever.

9 14. An operating mechanism for a typewriter comprising a frame separate from and adapted to support said typewriter, of 95 a reciprocatory actuating bar, a plurality of independently movable fingers carried by said actuating bar, a connecting lever pivotally supported on said frame adjacent to each of said fingers, normally out of the 100 path thereof, and adapted to be connected with the operable parts of said typewriter, and means for moving a selected one of said actuating fingers into such a position that the reciprocation of said actuating bar will 105 cause said finger to engage its connecting lever, and means for automatically restoring said finger to its inoperative position.

10 15. The combination, with a typewriter 110 having a plurality of operable parts, of a plurality of levers pivotally mounted at one end and having their other ends pivotally connected with the respective parts of said typewriter, an actuating bar mounted above said levers and having movement toward 115 and away from the same, a plurality of fingers pivotally mounted on said actuating bar and arranged in alinement with the respective levers, said levers lying normally out of the path of said fingers, and means 120 for imparting pivotal movement to a selected one of said actuating fingers to establish an operative relation between it and the corresponding lever.

11 16. The combination, with a typewriter 125 having a plurality of operable parts, of an actuating bar having reciprocatory movement, a plurality of fingers pivotally mounted on said bar and movable therewith, a plurality of connecting levers pivotally sup- 130

ported at one end and connected at their other ends with the respective operable parts of said typewriter, said levers being arranged immediately beneath the respective actuating fingers and each lever having a recess arranged in the normal path of its finger, and means to impart pivotal movement to a selected one of said fingers to move it out of alinement with said recess and cause it to engage and actuate its lever.

17. The combination, with a typewriter having a plurality of operable parts, of an actuating bar having reciprocatory movement, a plurality of fingers pivotally mounted on said bar and movable therewith, a plurality of connecting levers pivotally supported at one end and connected at their other ends with the respective operable parts of said typewriter, said levers being arranged immediately beneath the respective actuating fingers and each lever having a recess arranged in the normal path of its finger, and means to impart pivotal movement to a selected one of said fingers to move it out of alinement with said recess and cause it to engage and actuate its lever, said levers and said fingers having interlocking parts to maintain the same in operative engagement during the downward movement of said actuating bar.

18. The combination, with a typewriter having a plurality of operable parts, of an actuating bar, means for imparting constant reciprocatory movement to said bar, a plurality of fingers pivotally mounted on said bar, springs for holding said fingers in their normal positions, a plurality of levers pivotally supported beneath the respective fingers and operatively connected with the respective operable parts of said typewriter, said levers having recesses to receive the adjacent ends of said fingers, and a controlling device to move a selected one of said fingers out of alinement with said recess and thus establish an operative connection between said finger and its lever.

19. In an operating mechanism for a typewriter, an actuating member having bodily movement and having parts movable therewith and independently thereof, connecting members adapted to be connected with operable parts of the typewriter and arranged adjacent to the respective movable parts of said actuating member, means to move a selected one of the movable parts of said actuating member into a position to operatively engage the adjacent connecting member, and means to positively retain said part in such position during the full movement of said actuating member in one direction.

20. In an operating mechanism for a typewriter, an actuating member, a plurality of fingers movably mounted on said actuating member, a connecting member supported adjacent to each of said fingers and

normally out of the path thereof, means for moving a selected one of said actuating fingers into a position to operatively engage the adjacent connecting member and to hold the same in such position until said engagement has been accomplished, and other means to retain said fingers in such engagement until said connecting member has been fully operated.

21. In an operating mechanism for a typewriter, an actuating bar, a plurality of fingers movably mounted on said actuating bar, a connecting lever pivotally supported adjacent to each of said fingers and normally out of the path thereof, means for moving a selected one of said actuating fingers into operative relation with its connecting member, said finger and said connecting lever having interlocking parts, and a detent to hold said finger in a position to engage said lever during the first portion of the movement of said actuating bar, whereby said detent and said interlocking parts serve to retain said finger and said lever in operative relation during one complete movement of the actuation bar in one direction.

22. In an operating mechanism for a typewriter, an actuating bar, a plurality of fingers movably mounted on said actuating bar, a connecting lever pivotally supported adjacent to each of said fingers and normally out of the path thereof, means for moving a selected one of said actuating fingers into operative relation with its connecting member, said finger and said connecting lever having interlocking parts, a detent to hold said finger in a position to engage said lever during the first portion of the movement of said actuating bar, whereby said detent and said interlocking parts serve to retain said finger and said lever in operative relation during one complete movement of the actuating bar in one direction, and means to release said finger to permit it to return to its normal position upon the upward movement of said actuating bar.

23. The combination with a typewriter having a plurality of operable parts, of a plurality of levers connected with the respective operable parts of said typewriter, an actuating bar arranged adjacent said levers and having constant movement toward and away from the same, a plurality of fingers movably mounted on said bar, means to hold said fingers normally in inoperative positions relatively to the respective levers, means for moving a selected one of said fingers into operative relation with its lever and for retaining the same in such relation, and means for releasing said finger to permit it to be returned to its normal position when it has been disengaged from said lever.

24. The combination, with a typewriter having a plurality of operable parts of a

- plurality of connecting members connected with the respective operable parts of said typewriter, an actuating bar, a plurality of movable fingers mounted on said bar and movable into and out of operative relation with the respective connecting members, the corresponding fingers and connecting members having interlocking parts to retain them in operative relation, a device to engage a selected one of said fingers and move it into operative position with relation to its connecting member, a detent to retain said finger in its operative position until the coöperating parts of said finger and said connecting member have interlocked, and means for moving said device away from said finger as soon as said coöperating parts have interlocked.
25. The combination, with a typewriter having a plurality of operable parts, of connecting members connected with the respective operable parts of said typewriter, an actuating member having movable fingers adapted to be moved into and out of operative relation with the corresponding connecting members, a movable member having projections, and connecting devices interposed between said movable member and said fingers and adapted to be actuated by said projections to impart movement to the respective actuating fingers.
26. The combination, with a typewriter having a plurality of operable parts, of connecting members connected with the respective operable parts of said typewriter, an actuating member having movable fingers adapted to be moved into and out of operative relation with the corresponding connecting members, slide bars arranged in alinement with the respective actuating fingers, a series of two armed levers arranged adjacent to said bars and having one arm arranged in alinement with the adjacent end of the corresponding bar, a movable member arranged adjacent to the other arm of said levers, and projections carried by said movable member and adapted to engage said other arms of said levers to impart movement to said bars and actuate the respective fingers of said actuating device.
27. The combination, with a typewriter having a plurality of operable parts, of connecting members connected with the respective operable parts of said typewriter, an actuating member having movable fingers adapted to be moved into and out of operative relation with the corresponding connecting members, slide bars arranged in alinement with the respective actuating fingers, a series of two armed levers arranged adjacent to said bars and each having one arm arranged in alinement with the adjacent end of the corresponding bar, a movable member arranged adjacent to the other arm of said levers, projections carried by said movable
- member and adapted to engage said other arms of said levers to impart movement to said bars and actuate the respective fingers of said actuating device, and means for moving said bars out of alinement with the respective levers to interrupt the connection between said movable member and said actuating member.
28. The combination, with a typewriter having a plurality of key bars, of an actuating member, a plurality of connecting levers, links connecting said levers with the respective key bars, each of said links having an elongated loop at its upper end to receive the corresponding key bar, said loop being of a length greater than the width of said key bar to permit the latter to have movement therein, and means for connecting said actuating member with a selected one of said levers.
29. In an automatic operating mechanism for typewriters, selective actuating mechanism, a controlling device comprising a movable member having guides extending transversely to the line of its movement, and a trip device mounted to be moved along each of said guides into a position adjusted in relation to said actuating mechanism.
30. In an automatic operating mechanism for typewriters, selective actuating mechanism, a controlling device comprising a movable member having guides extending transversely to the line of its movement, a trip device mounted to be moved along each of said guides into a position adjusted in relation to said actuating mechanism, a gage arranged adjacent to said movable member, and means for engaging said trip devices to move them along said gage to their adjusted positions.
31. In an automatic operating mechanism for typewriters, selective actuating mechanism, a controlling device comprising a movable member having guides extending transversely to the line of its movement, a trip device mounted to be moved along each of said guides into a position adjusted in relation to said actuating mechanism, means for simultaneously moving a plurality of said trip devices into positions at one side of said movable member, and another device for moving said trip devices individually into adjusted positions along said guides.
32. The combination with a typewriter having operable parts, of an actuating mechanism, comprising a plurality of parts operatively connected with the respective parts of said typewriter, and a rotatable controlling drum having a plurality of slots formed in the periphery thereof parallel with its axis, and trip devices mounted in said slots for bodily adjustment along the same and having parts projecting beyond the periphery of said drum.
33. The combination with a typewriter

having operable parts, of an actuating mechanism comprising a plurality of parts operatively connected with the respective parts of said typewriter, a controlling device comprising a movable member having a series of guideways extending substantially parallel with the axis thereof, trip devices mounted for movement along said guideways and having parts projecting beyond the surface of said controlling device, and means for advancing said controlling device step by step as said trip devices are adjusted in the respective guideways.

34. The combination with a typewriter and a selective actuating mechanism to automatically operate the same, of a controlling device for said actuating mechanism having adjustable projections to determine the selective action of said actuating mechanism, said controlling device being removable to enable the form set up thereon to be preserved.

35. The combination, with a typewriter, and selective actuating mechanism for automatically operating said typewriter, of a controlling device for said selective actuating mechanism having movable parts adapted to be adjusted to different positions to determine the selective action of said actuating mechanism, said controlling device being removably mounted to permit of its removal to preserve the form set up thereon.

36. The combination with a typewriter having operable parts and selective actuating mechanism having movable members connected with the respective operable parts of said typewriter, of a movable controlling device for said selective actuating mechanism and connecting devices interposed between said controlling device and said actuating mechanism to transmit motion from the former to selected parts of the latter, said connecting devices having parts movable into inoperative positions to interrupt said connections.

37. The combination, with a typewriter having operable parts, and selective actuating mechanism having movable members connected with the respective operable parts of said typewriter, of a controlling device for said selective actuating mechanism, devices for connecting said controlling device with said actuating mechanism, each of said connecting devices comprising two parts arranged normally in alinement, whereby the movement of one part will actuate the other part, and means for moving one of said parts out of alinement with the other part to interrupt the connection between the controlling device and the actuating mechanism.

38. The combination, with a typewriter having operable parts, and selective actuating mechanism having movable members connected with the respective operable parts of said typewriter, of a controlling device,

connecting devices interposed between said controlling device and said actuating mechanism comprising levers adapted to be engaged and actuated by said controlling device, bars arranged normally in a position to be operated by the respective levers and connecting said levers with the respective members of said actuating mechanism, and means for moving said bars into inoperative positions relatively to the respective levers, thereby interrupting the connection between the controlling device and the actuating mechanism.

39. The combination, with a typewriter having operable parts, and selective actuating mechanism having movable members connected with the respective operable parts of said typewriter, of a controlling device, connecting devices interposed between said controlling device and said actuating mechanism comprising levers adapted to be engaged and actuated by said controlling device, bars arranged normally in a position to be operated by the respective levers and connecting said levers with the respective members of said actuating mechanism, means for moving said bars into inoperative positions relatively to the respective levers, thereby interrupting the connection between the controlling device and the actuating mechanism, a motor for imparting movement to said actuating mechanism, a controlling device for said motor, and a connection between the controlling device for said motor and the means for moving said bars.

40. The combination, with a typewriter, and automatic actuating mechanism therefor, of a controlling device for said automatic actuating mechanism, devices for connecting said controlling device with said automatic mechanism, means to render said connecting devices inoperative, a motor to impart movement to said automatic actuating mechanism, a controlling device for said motor, and a connection between said controlling device for said motor and the means for rendering said connecting devices inoperative.

41. The combination, with a typewriter comprising a paper carriage movable from one side of said typewriter to the other, selective actuating mechanism for said typewriter, and power mechanism for driving said actuating mechanism, a device operatively connected with said carriage to return the same to its normal position, a clutch connection between said device and said power mechanism, an operative connection between said clutch and said actuating mechanism, and a controlling device for said actuating mechanism.

42. The combination, with a typewriter comprising a paper-carriage movable from one side of said typewriter to the other, selective actuating mechanism for said type-

- writer, and power mechanism for driving said actuating mechanism, of a rotatable drum, a flexible connection between said rotatable drum and said carriage, a clutch connection between said drum and said power mechanism, an operative connection between said clutch and said actuating mechanism, and a controlling device for said actuating mechanism.
43. The combination, with a typewriter comprising a paper-carriage movable from one side of said typewriter to the other, selective actuating mechanism for said typewriter, and power mechanism for driving said actuating mechanism, of a rotatable drum, a flexible connection between said rotatable drum and said carriage, a clutch connection between said drum and said power mechanism, an operative connection between said clutch and said actuating mechanism, and an adjustable controlling device for said actuating mechanism to control the return of said carriage.
44. The combination, with a typewriter comprising a paper-carriage movable from one side of said typewriter to the other, selective actuating mechanism for said typewriter, and power mechanism for driving said actuating mechanism, of a rotatable drum, a flexible connection between said rotatable drum and said carriage, a clutch connection between said drum and said power mechanism, an operative connection between said clutch and said actuating mechanism, a controlling device for said actuating mechanism, and a trip device actuated by said carriage to disconnect said clutch mechanism and release said drum from said power mechanism.
45. In an automatic operating mechanism for typewriters, a controlling device comprising a movable member, trip devices carried thereby and a retaining device arranged above said movable member and having openings to receive the respective trip devices and hold them in adjusted positions.
46. In an automatic operating mechanism for typewriters, a controlling device comprising a movable member, trip devices adjustable transversely to the line of movement of said movable member, and a slotted device to retain said trip devices in adjusted positions.
47. In an automatic operating mechanism for typewriters, a controlling device comprising a movable member having a series of slots therein, trip devices adjustably mounted in said slots, and a slotted device extending over the face of said movable member to retain the trip devices in said slots and to prevent their movement from their adjusted positions.
48. In an automatic operating mechanism for typewriters, a controlling device comprising a movable member having a series of slots therein, trip devices comprising plates mounted in said slots and having reduced portions projecting beyond the face of said member, and a retaining device adapted to fit over said movable member and having openings to receive the reduced portions of said plates to retain said plates in said slots and to prevent the movement thereof from their adjusted positions.

In testimony whereof I affix my signature in presence of two witnesses.

J. H. PILLINGS.
